NEW YORK.

WINDING MECHANISM.

1,300,477.

Specification of Letters Patent. Patented Apr. 15, 1919.

Application filed April 27, 1918. Serial No. 231,109.

To all whom it may concern:

Be it known that I, JOHN F. O'CONNOR, a citizen of the United States, residing at Chicago, in the county of Cook and State 5 of Illinois, have invented a certain new and useful Improvement in Winding Mechanism, of which the following is a full, clear, concise, and exact description, reference being had to the accompanying drawings, 10 forming a part of this specification.

This invention relates to improvements in winding mechanism.

One object of the invention is to provide an efficient chain or other winding mechanism, more particularly adapted for hand 15 brakes of railway cars, and which is so arranged as to permit relatively rapid winding movement in taking up the slack in the chain and a slower but higher power ratio 20 movement for completing the winding or tightening movement.

Another object of the invention is to provide a winding mechanism of the character above indicated having a single operating 25 member adapted to effect a winding movement of one speed when said member is moved in one direction and a winding movement in the same direction at a different speed when said member is moved in the 30 opposite direction.

In the drawing forming a part of this specification, Figure 1 is an end elevational view of a hand brake for railway cars showing my improvements in connection therewith. Fig. 2 is a vertical, sectional view, taken substantially on the line 2—2 of Fig. 35 1. And Fig. 3 is a transverse, sectional view, taken substantially on the line 3—3 of Fig. 2.

40 In said drawing, 10 denotes a wall of a car to which my improved winding mechanism, in the form of a hand brake, is adapted to be secured. As shown, the brake includes a housing or casing A, a chain winding drum B, an operating lever C, a ratchet wheel D, a second ratchet wheel E, a release wheel F, and pinion G, together with other minor features hereinafter specifically described.

50 The casing A is of substantially hollow cylindrical form having an outer wall 11, intermediate wall or partition 12, and inner wall flange 13, said casing having suitably extended lugs or ears 16 by which it is rivet-

ed or otherwise secured to the wall of the 55 car. The inner wall flange 13 of the casing is inwardly offset so as to provide a suitable recess to accommodate a detachable inner wall plate 17, the latter having a central hub or boss 18 forming a suitable bearing for 60 the inner end of the hollow chain winding drum B. The intermediate partition 12 of the casing has the central portion 19 thereof offset so as to form a suitable bearing seat for a flange 20 formed on the drum B, and 65 said offset portion 19 is also centrally perforated, as indicated at 21, to form a bearing for the outwardly extended sleeve 22 of the drum. The casing A is cut away at the bottom, as indicated at 23, so as to provide 70 the necessary clearance for the brake chain, the upper link 24 of which is shown in the drawing and is attached to a flange 25 formed on the drum B.

Keyed to the sleeve 22 of the drum so as 75 to rotate in unison therewith is the ratchet wheel E, the latter having a peripheral series of ratchet teeth 26 and an inwardly extended hub 27 on which is rotatably mounted the combined ratchet and gear 80 wheel D. The wheel D on the outer side thereof, and arranged so as to coöperate with the ratchet teeth 26, carries a spring-controlled pawl 28 that engages with the ratchet teeth 26 for the purpose hereinafter 85 described. The ratchet teeth of the wheel D coöperate with a spring-controlled pawl 29 mounted in a suitable cup-shaped offset 30 formed in the casing A. It will be noted from an inspection of Fig. 3, that the pawls 90 29 and 28 are both arranged in the same direction, that is, they permit the wheels D and E to rotate counter-clockwise but normally prevent rotation of said wheels in a clockwise direction. From this, it will be 95 seen that when the wheel D is actuated in a counter-clockwise direction, it will necessarily rotate the wheel E and consequently the drum B therewith and when the pawl 28 is disengaged from the wheel E, as herein-after explained, the latter can rotate in a reverse or clockwise direction independently of the wheel D.

The operating lever C, as shown, consists of two sections 31 and 32, the upper or supporting section 31 being extended downwardly and formed on its lower end into a U-shape so as to form a suitable support for

a pin 34. The lever section 32, which is the handle proper, is forked at its upper end, as indicated at 35, and straddles the U-shaped lower end of the section 31 and is pivoted to the latter by said pin 34. The pinion G is also mounted within the U-shaped lower end of the lever section 31 and on the said pin 34.

By referring to Figs. 1 and 2, it will be seen that the lever sections 31 and 32 are provided with engaging beveled faces 36 so designed that, as viewed in Fig. 1, the handle or lever section 32 can not be swung about the pin 34 to the right of a line passing through the pin 34 and the axis of rotation of the drum B about which said lever, as an entirety, is adapted to be oscillated as will be understood.

Pivotedly mounted on the handle or lever section 32 is a spring-controlled pawl 37 which coöperates with the pinion G, said pawl 37 being so arranged as to permit rotation of said pinion G in a clockwise direction about the pin 34 but preventing counter-clockwise rotation thereof, as viewed in Fig. 3.

The release wheel F is keyed to the hub 38 of a plate 39 which is rotatably mounted on the sleeve 22 of the drum B. The hub 38 of the plate 39 is itself also journaled in a suitable bearing 40 formed in the outer wall 11 of the casing A, the plate 39 being located on the inner side of said wall 11, as clearly appears from Fig. 2. The plate 39, on its inner face, carries a preferably integral pin 41 adapted to travel in a circular path having a radius greater than the radius of the ratchet wheel E but of less radius than the distance from the axis of the wheel E to the pivot of the pawl 28 so that, when said pin 41 is moved in a counter-clockwise direction, as viewed in Fig. 3, it will effect disengagement of the pawl 28 from the ratchet wheel E, regardless of the position of the ratchet wheel E and its pawl 28. To hold the parts in assembled position, the through bolt 42 is employed which extends from the boss or hub 18 to the outer end of the device and has a washer 43 and nut 44 placed thereon.

In order to hold the upper section 31 of the lever against movement, for the purpose hereinafter described, I provide a latch 45 pivoted, as indicated at 46, to the casing A, said latch 45 being of hook-shape and adapted to engage over the outer arm of the U-shaped lower end of the lever section 31 but free of the lever section or handle 32.

The operation is as follows: To effect the winding or tightening of the chain while taking up the slack thereof, the operator throws the latch 45 out of engagement with the operating lever and then proceeds to oscillate the lever about the axis of rotation of the drum B. As the lever is swung to

the left, as viewed in Fig. 1, it is evident that the wheel D will be held stationary by the pawl 29 and consequently the pinion G will rotate freely in a clockwise direction. As the lever is then swung down, the tendency is for the pinion G to rotate in a counter-clockwise direction but on account of the pawl 37, this is prevented. Consequently, the pinion G and combined ratchet and gear wheel D will be locked and the latter rotated in a counter-clockwise direction, which is permitted by the arrangement of the pawl 29. As the wheel is thus rotated, it is evident that the ratchet wheel E will be rotated in the same direction and consequently the drum B, which is keyed to the wheel E, will also be rotated. In other words, the drum B will be rotated in unison with the operating lever C whenever the latter is swung as an entirety in a counter-clockwise direction. This movement may be continued by the operator until the slack in the chain is taken up and then, in order to effect the final winding or tightening movement of the chain and at an increased leverage ratio, the operator throws the latch 45 into engagement with the upper section 31 of the operating lever. Then, as the handle 32 is oscillated about the pin 34, it is evident that oscillation of said handle 32 in a clockwise direction will cause the pinion G to rotate in a similar direction, and this rotation of the pinion G will be transferred to the wheel D and the rotation of the drum continued as before but at an obviously slower rate and with more effective leverage.

The drum is, of course, prevented from accidental backward rotation or release by the pawl 29 acting through the interposed wheel D, pawl 28 and wheel E. When it is desired to release the brake chain, the operator grasps the release hand wheel F and gives it a slight turn sufficient to disengage the pawl 28 from the wheel E, whereupon the latter in unison with the drum B, is permitted a free rotation in a clockwise or release direction. In this connection, it will be noted that in releasing the brake chain, all danger of suddenly swinging the operating lever is avoided since to effect release, a complete disengagement of the operative elements between the operating lever and the wheel E must be accomplished. This is of practical importance in the use of railway hand brakes since frequent injuries to the brakemen are occasioned by the operating levers of the brakes striking the brakemen when the chains are released.

Although I have herein shown and described what I now consider the preferred manner of carrying out the invention, the same is merely illustrative and I contemplate all changes and modifications coming within the scope of the claims appended hereto.

I claim:

1. In a mechanism of the character described, the combination with a rotatable element, of an operating member having movement in opposite directions, means interposed between said member and said element for rotating the latter at one speed when said member moves in one direction, and means for changing the operative relation of said first named means to cause rotation of said element in the same direction but at a different speed when said member is moved in the reverse direction. 65
2. In a mechanism of the character described, the combination with a rotatable element, of an operating lever adapted for oscillation as an entirety about the same axis as said element rotates, pinion pawl and ratchet means interposed between said lever and element for effecting step by step rotation of the latter upon oscillation of the lever about said axis, and means for effecting oscillation of a portion of said lever about a different axis, said first named means, 70
- 25 rotating said element step by step, when said lever is oscillated about said different axis but with an increased leverage ratio. 75
3. In a mechanism of the character described, the combination with a rotatable element, of a manually operable member, pawl and ratchet mechanism including gearing interposed between said member and element for effecting a rotative movement of said element corresponding to movement of 80
- 35 said member, and means for changing the action of said gearing to rotate said element at a different speed upon actuation of said member. 90
4. In a mechanism of the character described, the combination with a rotatable element adapted to tighten a chain or the like, of an operating lever oscillatable about one axis as an entirety, a section of said lever being independently oscillatable about 95
- 45 a different axis, and means interposed between said section and said element arranged to effect rotative movement of said element at one speed when said lever is oscillated as an entirety and at a different speed when 100
- 50 said section only is oscillated. 105
5. In a mechanism of the character described, the combination with a rotatable element adapted to tighten a chain or the like, of an operating lever oscillatable about one axis as an entirety, a section of said lever being independently oscillatable about 110
- 55 a different axis, and means interposed between said section and said element arranged to effect rotative movement of said element at one speed when said lever is oscillated as an entirety and at a different speed when 115
- 60 said section only is oscillated, 120
6. In a mechanism of the character described, the combination with a rotatable chain winding drum, of an operating lever oscillatable about the same axis as the axis of rotation of said drum, said lever comprising two sections pivotally connected, 70
- means coöperable with said lever as an entirety for effecting rotative movement of said drum when said lever is moved in one direction, means for holding one section of said lever in fixed position and permitting 75
- independent movement of the other section, and means interposed between the last named section and the drum for effecting rotation of the latter upon oscillation of the said section. 80
7. In a hand brake for railway cars, the combination with a housing having a chain winding drum rotatably mounted therein, of a ratchet wheel rotatable in unison with the drum, a second ratchet wheel carrying 85
- a pawl coöperable with the first named ratchet wheel, means for disengaging said pawl and first named ratchet wheel, a pawl coöperable with the second named ratchet wheel, and operating means for the second 90
- named ratchet wheel. 95
8. In a hand brake for railway cars, the combination with a housing having a chain winding drum rotatably mounted therein, of a combined ratchet and gear wheel rotatable 100
- about the same axis as said drum, means interposed between said wheel and drum to effect rotation of the latter in unison with said wheel, a sectional lever, a pinion carried by said lever and coöperable with said 105
- wheel, a pawl coöperable with said pinion, and means for locking one section of said lever in fixed position and permitting independent movement of the other section thereof. 110
9. In a hand brake for railway cars, the combination with a housing having a chain winding drum rotatably mounted therein, of a combined ratchet and gear wheel rotatable about the same axis as said drum, means interposed between said wheel and drum to effect rotation of the latter in unison with said wheel, a sectional lever, a pinion carried by said lever and coöperable with said 115
- wheel, a pawl coöperable with said pinion, and means for locking one section of said lever in fixed position and permitting independent movement of the other section thereof, and means for rendering inoperative the first named means. 120

In witness that I claim the foregoing I have hereunto subscribed my name this 10th day of April, 1918.

JOHN F. O'CONNOR.
